UNITED STATES PATENT OFFICE

FUSAJIRO MAMIYA, OF LOS ANGELES, CALIFORNIA

DESIGN FOR A TRAFFIC-SIGNAL CASING

Application filed December 24, 1929. Serial No. 33,915. Term of patent 14 years.

To all whom it may concern:

Be it known that I, FUSAJIRO MAMIYA, a subject of the Emperor of Japan, residing in the city and county of Los Angeles and State of California, have invented a new and original and ornamental Design for Traffic-Signal Casing, of which the following is a specification, reference being had to the accompanying drawing, forming a part hereof.

In the drawings, Figure 1 is a side elevation of my traffic signal casing showing my new design, and illustrating the signal arm in one of its display positions; the opposite side of the casing being the same, and like-

wise unornamented. Fig. 2 is a rear elevation of the casing, the opposite view of the casing having an opening to accommodate the signal arm, and being otherwise unornamented.

The signal arm is disposed in the housing in non-display position, and is operative to angular display positions.

I claim:

The ornamental design for a traffic signal casing, substantially as shown and described.

In testimony whereof, I hereunto affix my signature.

FUSAJIRO MAMIYA.
